PACKAGED GALVANIC ANODES FOR
CATHODIC PROTECTION

Joseph G. Glesner and Melvin O. Robinson, Midland, Mich., assignors to The Dow Chemical Company, Midland, Mich., a corporation of Delaware

Application January 7, 1948, Serial No. 838

3 Claims. (Cl. 204—197)

1

This invention relates to packaged anodes for use in the cathodic protection of underground metals. It also concerns the containers for making such packaged anodes.

In galvanic systems for the cathodic protection of pipelines and other underground structures, sacrificial anodes of a metal electro-negative to the structure, usually magnesium, zinc, or aluminum, are buried in the earth near the structure and connected to it by electrical conductors. The resulting flow of current maintains the structure cathodic with respect to the soil and greatly minimizes its corrosion. In such service, it is often desirable, when using magnesium metal as a sacrificial anode, to bury it in a prepared bed or backfill designed to control the chemical nature of the anode environment.

In making cathodic protection installations, conventional practice has been to transport the sacrificial anodes and the backfill ingredients separately to the site. Each anode is then sunk in a hole dug for the purpose, after which the backfill ingredients are mixed and the mixture is tamped or otherwise placed around the anodes. This procedure, while effective, is cumbersome and occasionally results in the installation of a poorly mixed backfill. Efforts have therefore been made to develop a packaged anode, i. e. a preformed package containing an anode with the proper quantity of appropriate backfill already in place around it. Such a packaged anode could, of course, be installed very readily simply by burying it in the earth.

Two principal types of packaged anodes have been proposed heretofore; neither has been fully satisfactory. In one, the anode is embedded in a mass of backfill cemented together by a bonding agent. Such cemented backfills have been quite brittle, sometimes breaking off in chunks during handling. In the other type, the anode is centered in a water-permeable carton or sack which also contains the backfill in powdered form. Disadvantageously, paper cartons sufficiently water-permeable for the service have proved subject to puncture during transportation. Sacked anodes, though seldom thus damaged, are often unusable in that the anode shifts out of position during the jarring attendant on shipping and is no longer centered in the backfill on arrival at the site.

In view of these difficulties, it is the principal object of the present invention to provide an improved packaged anode which is not subject to the disadvantages mentioned. A related ob-

2

ject is to provide a simple cloth container or sack for making packaged anodes which positively retains the anode centered in the backfill.

5 The improved container according to the invention consists essentially of an inner water-permeable sack closed near the bottom by a transverse seam at a spaced distance above the bottom and an outer water-permeable sack enclosing the inner sack and secured along its bottom to the bottom of the inner sack. The galvanic anode is placed within the inner sack above the seam and is surrounded by comminuted backfill which fills the space between the inner and outer sacks. In this construction, the anode is positively retained centered in the backfill under all conditions to which the packaged anode is subjected.

10 The invention, in a preferred form, will be further explained with reference to the accompanying drawing, in which:

Fig. 1 is an elevation of a finished packaged anode with the top tie in place;

Fig. 2 is a sectional elevation taken at right angles to the view of Fig. 1 and along the line 2—2 of Fig. 3, before the top is tied;

Fig. 3 is a horizontal section through the packaged anode of Figs. 1 and 2, along the line 3—3 of Fig. 2;

Fig. 4 is a cutaway view of the double-sack container of Figs. 1 to 3 before the anode and backfill are inserted; and

Fig. 5 is an elevation of another form of finished packaged anode.

15 In the drawings, the galvanic anode is an elongated cylindrical body of magnesium metal 6 having a central core 7 of galvanized iron pipe cast integrally with it. An insulated copper lead wire 8 is soldered to the inside of the pipe core 7 at its upper end, the joint being protected by an insulating caulking such as pitch 9. The anode is surrounded by a suitable comminuted backfill 10, such as a powdered mixture of 75 percent by weight gypsum, 20 percent bentonite, and 5 percent sodium sulfate.

20 The anode and backfill are placed in a special container comprising an elongated inner sack 11 of length and diameter greater than those of the anode 6 and an outer sack 12 of length and diameter greater than those of the inner sack. As shown, the inner sack 11 is made of coarse mesh, e. g. a cotton cord net six strands to the inch, which is stitched longitudinally along a full-length seam 13 to form a tube. This inner sack is closed near its bottom by a transverse

stitched seam 14 at a spaced distance above its bottom edge. The outer sack 12 is made of water-permeable cloth of sufficient fineness to retain the comminuted backfill without loss, muslin or canvas being ordinarily used. This sack is likewise sewed longitudinally along a full-length seam 15.

In the finished container, as shown particularly in Fig. 4, the inner sack 11 is centered inside the outer sack 12 with the bottom edges of the two sacks registering. These edges are then turned over and stitched together forming a common hem 16 which holds the two sacks firmly together and prevents the lower end of the inner sack from moving either longitudinally or laterally relative to the outer sack.

In making the finished packaged anode, the magnesium anode 6 is slipped into the inner sack 11 until it rests on the lower seam 14. Powdered backfill 10 is then poured into the space between the inner sack 11 and the outer sack 12 until it completely surrounds the anode. It may be necessary to shake the assembly somewhat to insure that the backfill flows under the anode, i. e., into the spaces between the bottom hem 16 of the outer sack and the lower seam 14 of the inner sack. Filling is continued until the level of the backfill is somewhat above that of the top of the anode. The upper ends of the inner and outer sacks are then gathered together and secured with a cord or wire tie 17, which serves not only to close the sacks but also to hold the upper end of the inner sack from moving relative to the outer sack. The lead wire 8 of the anode is brought out through the tie.

In an optional construction shown in Fig. 5, the common bottom corners of the inner and outer sacks are folded over and hemmed dog-eared, as at 18. This construction strengthens the corners somewhat and also makes the packaged anode easier to install.

In a typical packaged anode according to the invention, the anode is a cylindrical body of magnesium 4 inches in diameter and 20 inches long. The inner sack is 6-mesh net, 5 inches in diameter and 28 inches long, with the lower seam 2 inches above the bottom edge. The outer sack is muslin 7 inches in diameter and 3 inches longer than the inner sack.

In using the packaged anode of the invention in a cathodic protection installation, it is necessary simply to dig a hole in the earth near the structure to be protected, insert the packaged anode, tamp the earth firmly around it, and connect the lead wire from the anode to the structure. In dry soil it is desirable to pour water on the newly installed packaged anode to hasten the beginning of galvanic action. The number and spacing of the packaged anodes required for a given installation are determined by procedures well known to corrosion engineers.

It will be appreciated that the present invention

is concerned with improved packaging for galvanic anodes, and is applicable with all galvanically active metal anodes, regardless of the metal of which they may be formed. Likewise, the chemical nature of the backfill does not form a part of the invention, several such backfills being well known in the art. The specific gypsum, bentonite, and sodium sulfate backfill mentioned above is claimed in a co-pending application Serial No. 982 filed January 7, 1948, now Patent No. 2,480,087.

What is claimed is:

1. A container for making packaged galvanic anodes comprising elongated inner and outer water-permeable tubular sacks, each closed at its lower end by a transverse seam, the inner sack being spaced an appreciable distance above the bottom of the outer sack by a strip of sack material which holds the inner and outer sacks together only along their parallel bottom seams.

2. A packaged anode for use in cathodic protection systems comprising inner and outer water-permeable sacks, each closed at its lower end by a transverse seam, the bottom of the inner sack being spaced an appreciable distance above the bottom of the outer sack by a strip of sack material which holds the inner and outer sacks together only along their parallel bottom seams, a galvanically active metal anode having a wire conductor secured to one end thereof contained within the inner sack, and a comminuted anode backfill composition filling the space between the inner and outer sacks so as to surround the anode.

3. A packaged anode according to claim 2 wherein a tie closes the inner and outer sacks centrally at the top with the wire conductor extending therethrough.
